UNITED STATES PATENT OFFICE.

WILLIAM KAISLING, OF CHICAGO, ILLINOIS, ASSIGNOR TO KELLOGG SWITCHBOARD AND SUPPLY COMPANY, OF CHICAGO, ILLINOIS, A CORPORATION OF ILLINOIS.

PLUG.

Application filed January 30, 1924. Serial No. 689,389.

My invention relates to improvements in connecting plugs, and has to do more particularly with that class of plugs which are adapted to have connected thereto one or 5 more instrumentalities. The plug of my invention is particularly adapted for use in connection with radio receiving sets to which may be connected a number of head phones through the medium of the plug and jacks 10 of the receiving set; and an object of my invention is to construct a connecting plug of a few and simple parts, so arranged as to be easily assembled and at the same time very durable and strong. 15 It is desirable at times to connect more than one head phone set to the connecting plug, so that when the connecting plug is inserted in the various jacks to connect to the various circuits, more than one individual 20 may listen in at the same time. Various types of plugs have been marketed to accomplish the connection of more than one head- phone set at the same time such as multiple and series connection plugs and various 25 type of screw fasteners are provided for fastening the cord tips of the headphone sets to the respective terminals of the connecting plug. This type of screw terminal has its disadvantages because when connecting more than one set of headphones to the plug terminals, the cord tips must be held in position while the terminal screw is tightened to hold the cord tips in position.

The plug of my invention is of the series 30 type in which the plug is provided with spring terminal means, which obviates the necessity of screw terminals. The cord tips of the head sets are inserted under the spring terminals and the tension of the 35 spring terminals is such as to hold the cord tips in engagement therewith against displacement.

A feature of my invention is the provision of a novel spring assembly, in which a 40 pair of spring terminals are provided, which are conductively connected to the tip and sleeve conductors of the plug, and in association therewith is a spring terminal comprising a pair of spring members, insulated 45 from the tip and sleeve conductors, to provide series connecting means for a pair of head phone sets.

Another feature of my invention is the provision of a conducting bolt, which, in 50 addition to serving as a conductor extending

to the tip of the plug, it also serves as clamping means for securing the spring terminal combination in position and also for securing the sleeve of the plug in position.

For a more complete understanding of my 60 invention, reference may be had to the accompanying drawing in which like reference characters in the several views denote like parts, and in which

Fig. 1 is a view of the connecting plug 65 assembled;

Fig. 2 is a view of the connecting plug with the handle or sleeve in section to clearly illustrate the plug;

Fig. 3 is a view similar to Fig. 2 illustrating another view of the plug;

Fig. 4 is an enlarged sectional view taken on the line 4—4 of Fig. 2;

Fig. 5 is an enlarged end view of the plug; 75

Fig. 6 is a disassembled perspective view of the spring terminals and an insulating block associated therewith.

Referring now in detail to my invention as illustrated in the accompanying drawing, the plug comprises a shallow cup shaped member 2 internally threaded and a cylindrical sleeve 3 which is provided with a central orifice which receives the insulating sleeve 4. The sleeve 3 is provided with a reduced end portion 5 which forms an annular shoulder 6. A central orifice 7 in the cup member 2 is of a size to receive the end portion 5 of the sleeve member 3 and its annular shoulder 6 rests against the face 8 of the 90 cup member 2 when in position in said orifice 7. A conducting stem or bolt 9 extends through the insulating sleeve 4, its one end 10 being threaded and its forward end is provided with an integrally formed 95 spherical shaped tip contact member 11 which is insulated from the conducting sleeve 3 by means of the insulating bushing 12. A spring terminal 13 angular in shape is provided with a disc portion 14 having a central orifice 15 of a size to receive the protruding end of the insulating sleeve 4. The disc portion 14 of the spring terminal 13 is provided with a pair of orifices 16 diametrically opposite each other which are 100 adapted to receive a pair of studs 17 of suitable insulation material which are secured to the cup member 2 in orifices 18 by means of a drive or force fit, and which extend rearwardly into the cup member 2. 110

105

The disc portion 14 of the spring terminal 13 registers with the inner face of the cup member 2 of the plug, but is insulated from the conducting bolt 9 by means of the insulating sleeve 4, and this terminal 13 forms the terminal of the conducting sleeve 3 of the plug. A terminal 19 angular in shape is also provided with a disc portion 20, and is provided with a central orifice 21 of a size 5 to receive the protruding end of the insulating sleeve 4. The disc portion 20 of the terminal 19 is also provided with a pair of diametrically opposite orifices 22 which are adapted to receive the studs 17. An insulating plate or bushing 23 provided with a central orifice of a size to receive the protruding end of the insulating bushing 4 and a pair of diametrically opposite orifices of a size to receive the studs 17 rests between the 10 disc portion 14 of the terminal 13 and the disc portion 20 of the terminal 19 to insulate one from the other, the said insulating sleeve 4 insulating the terminal 19 from the connecting bolt 9.

15 25 A terminal 24 angular in shape and provided with a disc portion 25 is provided with a central orifice 27 of a size to receive the connecting bolt 9 and a pair of diametrically opposite orifices 28 are adapted to receive the studs 17. An insulating plate or bushing 29, provided with a central orifice of a size to receive the connecting bolt 9, and a pair of diametrically opposite orifices of a size to receive the studs 17, rests between the disc 30 portion 25 of the terminal 24 and the disc portion 20 of the terminal 19 to insulate one from the other. The threaded end 10 of the conducting bolt 9 protrudes through the aligned central orifices 15, 21 and 27 in the disc portions 14, 20 and 25 of the terminals 13, 19 and 24 and the central orifices in the insulating bushings 23 and 29 and a slotted nut 130 having screw threaded engagement with the threaded end 10 of the conducting bolt 9 is screwed down against the face of the disc 25 of the terminal 24 and clamps the terminal discs 14, 20 and 25 and insulating bushings 23 and 29 in position and at the same time forms a conducting means between the tip contact 11 of the conducting bolt 9 and its terminal 24. The studs 17 which as before described are of suitable insulating material extend through the aligned diametrically opposite orifices 16, 22, 28 in the disc portions 14, 20 and 25 of the terminals 13, 19, and 24 and the insulating bushings 23 and 29 to hold the terminals 13, 19 and 24 and bushings 23 and 29 against turning on the protruding end of the insulating sleeve 4 and conducting bolt 9.

35 40 45 The terminal 13 is provided with a rearwardly extending spring member 30 formed to bend inward and the terminal 19 is provided with a rearwardly extending bifurcated spring member which bifurcations form a pair of spring members 31 and 31', formed to bend inwardly. The terminal 24 is also provided with a rearwardly extending spring member 32 formed to bend inwardly. An insulating block 33 is provided with a central 70 orifice 34 of a size to receive the end 10 of the conducting bolt 9. An annular recess 35 concentric with the orifice 34 is provided, into which the nut 130, which clamps the terminal members 13, 19 and 24 and insulating bushings 23 and 29 together, extends to permit the block 33 to rest against the face of the disc 25 of the terminal 24. The face 36 of the block 33, which rests against the face of the disc 25 of the terminal 24 is also provided with a pair of diametrically opposite orifices 37, into which the end of the studs 17 extend to prevent turning of the block 33 on the conducting bolt 9. The block 33 is secured on the conducting bolt 9 by means 75 of a slotted nut 38 which has screw threaded engagement with the threaded end 10 of the conducting bolt 9, the said nut 38 resting in a suitable annular recess 39 in the rear face of the block 33. The block 33 is provided with flat faces 40 and 41, which respectively engage the bifurcated ends of the spring members 30 and 32 of the terminals 13 and 24, and spring members 31 and 31' of the terminal 19, when the block 33 is inserted 80 between the spring members 31 and 31' of the terminal 19 and the spring members 30 and 32 of the terminals 13 and 24, and force them outward against their normal tension. The faces 40 and 41 of the block 33 are provided 85 respectively with grooves 42 and 43, there being two grooves 42 in the face 40 in juxtaposition with the spring members 30 and 32 of the terminals 13 and 24, and grooves 43 of which there are two in the face 41 of the block 33 are in juxtaposition with the spring members 31 and 31' of the terminal 19. A form of cord tip that may be used is illustrated at 45 in Fig. 3.

90 95 100 105 110 115 120 125 130 Now to insert the cord tips such as 45 of a head phone set into engagement with the tip terminal 24 and sleeve terminal 13 of the plug all that is necessary is to force the cord tips 45 into the two grooves 42 in the face 40 of the block 33 against the normal tension of the spring members 30 and 32 of the terminals 13 and 24. The tension of the spring members 30 and 32 are such as to hold the cord tips in the grooves 42 in the face 40 of the block 33 against displacement and insure a positive connection between the spring members 30 and 32 of the terminals 13 and 24 and the cord tips at all times.

I provide a protective sleeve or handle 46 of suitable insulating material one end of 130 which is threaded and has screw threaded engagement with the cup member 2 of the plug. This handle or sleeve serves as a cover or enclosing member for the plug and also as a handle for grasping the plug. The

handle 46 is also provided with a pair of orifices 47 for the stay cords of the head set cords for purposes as will now be described.

To relieve the strain from the cord, should the plug be accidentally withdrawn by grasping the cord instead of the handle of the plug, a stay cord is inserted through the orifice 47 in the handle 46 of the plug and tied so as to allow slack in the individual conductors leading to the cord tips so that the cord tips will not be accidentally withdrawn from under the spring members 30 and 32 of the terminals 13 and 24.

Assuming that another head phone set is to be connected to the plug of my invention, the cord tip of the head phone set connected to spring member 32 marked 1 in the drawing for the purpose of description is withdrawn from the groove 42 in the face 40 of block 33 and inserted in the groove 43 in the face 41 of the block 33 under the spring member 31' of the terminal 19 opposite the spring member 32 marked 1. The cord tips of the second head phone set to be connected to the plug are now inserted in the grooves 42 and 43 in the faces 40 and 41 of the block 33 under the spring member 30 marked 2 in the drawing of the terminal 13 and the spring member 31 of the terminal 19. From the previous description it will be remembered that the terminal 19 is insulated from the terminals 13 and 24 and the conducting bolt 9, but as the spring members 30 and 32 of the terminals 13 and 24 are conductively connected to the tip and sleeve conductors 11 and 3 it is readily apparent that when the cord tips of one head set are connected to the spring members 32 and 31' of the terminals 24 and 19 and the cord tips of another head set are connected to the spring members 30 and 31 of the terminals 13 and 19 that the two head phone sets are thus connected in series.

It may be seen that it is a very simple matter to connect a head phone set to the plug of my invention without the usual trouble of loosening screws and holding the cord tips in position while the screws are again tightened, and especially so when trying to connect two head phone sets to the plug at the same time.

While I have described a particular form of my invention it is to be understood that changes and modifications will readily suggest themselves to those skilled in the art and I therefore aim to cover all such changes and modifications as come within the spirit and scope of the appended claims.

What I claim as new and desire to secure by United States Letters Patent is:

1. In a connecting plug of the character described comprising a tip conductor member and a sleeve conductor member, a cup member provided with a central orifice for receiving one end of said sleeve conducting

member and supporting the same, a conducting bolt extension for said tip conductor member, a terminal insulated from the terminals of said tip and sleeve members provided with a pair of integrally formed rearwardly extending spring members, spring terminals for said tip and sleeve members provided with integrally formed rearwardly extending members, said conducting bolt extension securing said tip member in association with said sleeve member and clamping said spring terminals to said cup member, and means secured to said cup for preventing rotation of said terminals relatively to said conducting bolt extension. 80

2. In a connecting plug of the character described comprising a tip conductor member and a sleeve conductor member, a cup member for supporting said sleeve member, a conducting bolt extension for said tip conductor member, spring terminals for said tip and sleeve conducting members, integrally formed rearwardly extending spring members for said terminals, a terminal insulated from the terminals of said tip and sleeve members provided with a pair of integrally formed rearwardly extending spring members, said conducting bolt extension securing said tip member in association with said sleeve member and clamping the terminals of said tip and sleeve members and said other terminals to said cup member. 95

3. In a connecting plug of the character described comprising a tip conductor member and a sleeve conductor member a cup member for supporting said sleeve member, a conducting bolt extension for said tip conductor member, spring terminals for said tip and sleeve conducting members, integrally formed rearwardly extending spring members for said terminals, a terminal insulated from the terminals of said tip and sleeve members provided with a pair of integrally formed rearwardly extending spring members, a block for separating said rearwardly extending spring members, said conducting bolt extension securing said tip member in association with said sleeve member, and said spring terminals and said block to said cup member. 110

4. In a connecting plug of the character described comprising a tip conductor member and a hollow sleeve conductor member, a cup member for supporting said hollow sleeve member, a conducting bolt extension for said tip conductor member extending through said hollow sleeve member, spring terminals for said tip and sleeve members and insulating bushings for insulating one from the other, a terminal member insulated from the terminals of the said tip and sleeve conductor members provided with a pair of integrally formed rearwardly extending spring members, rearwardly extending integrally formed spring members for said 125 130

- spring terminals, studs secured to said cup member passing through said spring members and said bushings to prevent said terminals from rotating relative to each other on said conducting bolt which clamps said terminals and bushings to said cup member.
5. In a connecting plug of the character described comprising a tip conductor member and a hollow sleeve conductor member,
- 10 a cup member for supporting said hollow sleeve member, a conducting bolt extension for said tip conductor member extending through said hollow sleeve member, spring terminals for said tip and sleeve members, provided with rearwardly extending spring members, another terminal insulated from said tip and sleeve spring members provided with a pair of integrally formed rearwardly extending spring members, said
- 15 20 conducting bolt clamping said tip and sleeve terminals in conductive relation with their respective tip and sleeve conductor members and said other terminal to said cup member.
6. In a connecting plug of the character described comprising a tip conductor member and a hollow sleeve conductor member, a cup member for supporting said hollow sleeve member, a conducting bolt extension of said tip member extending through said hollow sleeve for securing said tip member to said sleeve member and said sleeve member to said cup member, tip and sleeve terminals for said tip and sleeve members, a terminal insulated from said tip and sleeve terminals, said terminals clamped to said cup member by said bolt, rearwardly extending spring members for said tip and sleeve terminals and a pair of rearwardly extending spring members for said other terminal, said rearwardly extending spring members of said tip and sleeve terminals forming engaging means for connection to the terminals of a head set, said spring members of said other terminal forming means for connecting a second pair of head sets to said terminals in series connection.
7. In a connecting plug of the character described comprising a tip conductor member and a hollow sleeve conductor member, a cup member for supporting said hollow sleeve member, a conducting bolt extension of said tip member extending through said
- 25 30 35 40 45 50 55 60 65 70 75 80 85 90 95
- hollow sleeve for securing said tip member to said sleeve member and said sleeve member to said cup member, tip and sleeve terminals for said tip and sleeve members, a terminal insulated from said tip and sleeve terminals, said terminals clamped to said cup member by said bolt, rearwardly extending spring members for said tip and sleeve terminals and a pair of rearwardly extending spring members for said other terminal, said rearwardly extending spring members of said tip and sleeve terminals forming engaging means for connection to the terminals of a head set, said spring members of said other terminal forming means for connecting a second pair of head sets to said terminals in series connection.
8. In a connecting plug of the character described comprising a tip conductor member and a hollow sleeve conductor member, a cup member for supporting said hollow sleeve member, a conducting bolt extension of said tip member extending through said hollow sleeve for securing said tip member to said sleeve member and said sleeve member to said cup member, tip and sleeve terminals for said tip and sleeve members, a terminal insulated from said tip and sleeve terminals, said terminals clamped to said cup member by said bolt, rearwardly extending spring members for said tip and sleeve terminals and a pair of rearwardly extending spring members for said other terminal, said rearwardly extending spring members of said tip and sleeve terminals forming engaging means for connection to the terminals of a head set, said spring members of said other terminal forming means for connecting a second pair of head sets to said terminals in series connection, and a block secured to said cup member by said bolt for separating said tip and sleeve spring members from the spring members of said other terminal.
9. Signed by me at Chicago, in the county of Cook and State of Illinois, this 28th day of January, 1924.

WILLIAM KAISLING.
